Primary Examiner — Rebekah A Caruso(74) *Attorney, Agent, or Firm* — Wolf, Greenfield & Sacks, P.C.(57) **CLAIM**

The ornamental design for a holder, as shown and described.

DESCRIPTION

FIG. 1 is a top, front, right side perspective view of a holder showing a first embodiment of my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a top, front, right side perspective showing a second embodiment thereof;

FIG. 9 is a left side elevation view of FIG. 8;

FIG. 10 is a right side elevation view of FIG. 8;

FIG. 11 is a front elevation view of FIG. 8;

FIG. 12 is a rear elevation view of FIG. 8;

FIG. 13 is a top plan view of FIG. 8; and,

FIG. 14 is a bottom plan view of FIG. 8.

The long dash-short dash broken lines in the figures represent boundaries of the claimed design and form no part thereof. All other broken lines represent portions of the holder that form no part of the claimed design.

1 Claim, 7 Drawing Sheets(56)
